Specification of Letters Patent. Patented June 29, 1915.

Application filed September 23, 1907. Serial No. 394,187.

To all whom it may concern:

Be it known that we, CHARLES F. KETTERING and WILLIAM A. CHRYSST, citizens of the United States, residing at Dayton, in the county of Montgomery and State of Ohio, have invented certain new and useful Improvements in Cash-Registers, of which we declare the following to be a full, clear, and exact description.

10 This invention relates to cash registers and has among its objects the improvement of the release mechanism for such machines. It is advisable to retain such machines locked to prevent tampering therewith but 15 some simple method of releasing the machine should be employed. In this invention the machine is intended to be released by a depression of the manipulating devices, herein shown as a lever and bank of keys.

20 An additional object is to provide a release mechanism requiring the operation of two manipulative devices before the machine will be finally released. This gives the proprietor an additional check on the operations inasmuch as in order to operate the machine the clerk or employee must actuate 25 two different mechanisms.

As the machine is shown, it is adapted to be operated by an electric motor and therefore 30 a further object is to provide an improved circuit closer and clutch mechanism controlled by the machine and adapted to be placed in an ineffective condition near the close of the operation.

35 A further object is to provide a machine for compelling the operation of the two controlling devices in proper sequence.

With these and incidental objects in view, the invention consists in certain novel features of construction and combination of 40 parts, the essential elements of which are set forth in appended claims and a preferred form of embodiment of which is hereinafter described with reference to the drawings 45 which accompany and form part of this specification.

Of said drawings, Figure 1 is an end elevation of the left hand end of the machine. Fig. 2 is a transverse vertical section showing a bank of controlling keys. Fig. 3 is a rear elevation with the casing partly broken away to show the motor connection. Fig. 4 is a detail of the parts shown in Fig. 3 but seen from the reverse direction. These

parts comprise the lock arm and the circuit 55 closing lever. Fig. 5 is an end elevation of the motor and the clutch connection. Fig. 6 is a detail of the lock arm shown in Figs. 4 and 5, and Fig. 7 is a diagram of the motor circuit.

60 The invention is shown as applied to a well known type of machine now on the market, a complete description of which is to be found in a patent to Cleal and Reinhard, No. 580378, granted April 13, 1897, 65 together with a patent to Carroll, No. 703639, granted July 1, 1902, but it is to be understood that the invention is applicable to many other types of machines and is shown merely for convenience with the particular type referred to.

70 The Carroll patent cited shows a multiple counter machine in which the starting lever is adapted to be moved differentially to determine which one of the multiple counters 75 shall be placed in connection with the operating device. The lever in said patent is arranged to directly release the machine. In this invention, the same lever is used, although with a slightly different construction 80 of the releasing device, and as an additional precaution the levers are arranged so that the depression of some one of a bank of keys is required in order to completely release the machine. This is particularly of advantage in connection with 85 motor operated machines inasmuch as the exact positioning of the lever at first requires some little care. If the motor started from the lever it might easily be that the 90 circuit would be closed before the lever had reached the desired position and a wrong registration therefore made.

95 By coupling up the motor to the bank of keys and finally controlling the motor from said bank this difficulty is avoided inasmuch as it is an easy matter to depress the proper key quickly. The lever when pinched is arranged to move the arms of a toggle past the center thereby bringing into play a coil 100 spring which tends to move the said toggle and a lock device to a release position, but such release is prevented until the depression of a key which moves a pin in the key detent out of the path of an arm connected 105 to the toggle. When the pin is so moved the spring may complete the release, at the same time locking the key from movement

and preventing a depression of another key in the same bank. The release device is arranged to connect the motor clutch and close the circuit for the motor so that the machine immediately starts to operate. Near the end of the operation, a cam actuated from the main operating shaft restores the lock device to lock position thereby preparing for a disengagement of the clutch and the breaking of the motor circuit. The lever and its attached mechanism is best shown in Fig. 1. This lever 13 is pivoted on the main rod 14 and is provided with a segment rack 15 which is adapted to control the position of the rotatable counter carrier. The counters are not shown, however, as the present invention does not relate particularly to them and another device might be operated by the lever if desired. Mounted on the outward end of the lever is a bent arm 16 with a projection 17 adapted to engage and depress a bar 18 carried by parallel arms 20 which are pivoted on the lever 13. The bar 18 carries a lug 21 adapted to ride on the circular edge 22 of a plate 23, this plate being carried on two connected arms 24 and 25 pivoted respectively rigidly on the shaft 26 and loosely on the pin 27. Outside the path of movement of the lug 21 is index plate 28 having a series of notches, one for each lever position; into any one of which the lug 21 is adapted to move.

It will be seen from the drawing that in order to move the lever 13 it is necessary first to withdraw the lug 21 from the notch in which it happens to be of the index plate 28, and this is accomplished by rocking the arm 16 around its pivot and thereby depressing the bar 18. The consequent depression of lug 21 clearly moves the circular piece 23 thereby rocking the arm 24 and its pivot shaft 26. Also rigidly mounted on this shaft is a rearwardly extended arm 31 adapted to engage an anti-friction roller 32 mounted on one of two toggle arms 33 and 34. It will be evident that when the lever 16 is pinched the arm 31 will be slightly elevated and will thereby lift the two toggle arms. The toggle arm 34 is journaled on a pin 35 while the arm 33 is carried by a pin 36 forming a floating pivot.

As seen from the drawing, the straight line from pivot 35 to pivot 36 passes above the connecting pin 37 of the two toggle arms but the movement of the arm 31 before referred to serves to rock the toggle arms so that the pivot 37 is above the straight line joining the pivots 35 and 36 and a further movement of the toggle may then be given. The further movement of the toggle referred to is adapted to be caused by a coil spring 41 which moves an operating crank arm 42 mounted on a stub shaft 43; said crank arm also being engaged with the toggle arm 33 by a link 44 pivoted on

the toggle arm at 36. The spring is normally under tension and tends to rock crank arm 42 in a clockwise direction as shown on the figure, but such movement is prevented by the toggle. When, however, the center pivot 37 of the toggle is raised above the straight line joining the pivots 35 and 36 the spring 41 can then move the system of levers farther if it were not for mechanism yet to be described. 75

The link 44 has an upwardly extended arm 46 pivoted at 47 to a crank arm 48 rigidly mounted on a shaft 49. This shaft extends across the machine and, as shown in Fig. 2, in the plane of the key bank has a crank arm 50 having an upwardly extended projection 51. A bank of keys 52 is adapted to finally release the mechanism by a device now to be described. Each key is provided with a cam plate 53 which when the key is depressed engages a cam slot 54 in a segmental detent 55 and thereby elevates said detent. The detent plate 55 has mounted on a radial arm thereof a pin 56 which in a normal position of the parts is directly above the projection 51 of the crank arm 50. Clearly when the toggle is raised as above described the spring will move the system of levers thereby rocking the shaft 49 until the projection 51 engages and is stopped by 95 the pin 56 on the detent plate. When the key is depressed the pin 56 is carried above the projection 51 and the spring 41 then immediately moves all of the elements connected therewith causing the cutaway section of the crank arm 50 to surround the pin 56 thereby retaining the detent plate 55 in an elevated position and preventing the depressed key 52 from being released. 100

The rocking of shaft 43 controls the release of the machine and it will be seen that by the construction described a quick movement of the release arm is provided for. This is of advantage in the type of machine referred to for the reason that a movement of the locking device to release position is entirely out of the control of the operator when once it starts to move. Clearly the crank arm 50 cannot move more than a very slight distance until the detent pin 56 is completely out of its path. When the pin 56 is out of the path of the arm the system of levers immediately moves under force of the spring 41 to complete release position and nothing the operator 110 can do will have any retarding effect on this release movement. The construction also prevents the release of the depressed key after the machine has been released because the release movement of the locking device also causes a positive lock of the key. As the mechanism is shown, there is a two bank control for the machine; that is, to release the mechanism, the lever 16 must be operated and the key 52 must also be de- 115 120 125 130

pressed. This is of advantage in providing a double control over the movements of the operator inasmuch as it is requisite in order to release the machine that the lever be set to cause an operation of the system and that the proper key 52 be depressed in order to provide for indicating some desired characteristic of the transaction.

It is to be noted that no release of the machine should be possible except with the lever 13 exactly in one of its separate positions as it is only in such position that some one of the counters is exactly positioned for operation. To prevent a release of the mechanism except when the lever is properly positioned is the purpose of the index plate 28 and some other parts. The link 44 as shown in Fig. 1 is provided with an anti-friction roller 61 which is directly in front of the end of the arm 31, when the said arm is raised by the pinch lever 16. Clearly therefore if the arm 31 is raised no release of the machine will be obtained even by the depression of key 52 inasmuch as the arm 31 will prevent a rearward movement of the roller 61 and the arm 44 carrying the roller. In order to release the roller 61 it is necessary to permit the depression of arm 31 but this is only possible when the lug 21 is in position to pass completely into one of the notches of the index plate 28. This mechanism therefore prevents a release of the machine except when the lever is exactly in one of its proper positions.

The construction described compels the proper sequence of operation of the lever and the bank of keys; it being desired that the lever shall be operated first and that the machine shall be finally released by the operation of the key. It will be clear that if the key 52 is first depressed the detent plate 55 will be elevated but no effect will be produced on the locking device inasmuch as the toggle prevents any movement thereof. Moreover, the key will immediately return to its prior position under pressure of the usual key spring as there is nothing to retain the detent plate in its elevated position. When, however, the pinch lever is first operated and the toggle broken, the subsequent depression of a key carries the pin from over the projection 51 allowing a complete release of the mechanism.

As before stated, the machine locking device is intended to control the motor clutch and close the electric circuit for the motor contacts where the motor is used. The locking device, however, is clearly applicable to machines in which no motor is used or a machine having a motor of other types than electric. If a motor is used, such for example as a driving belt, the clutch will still be of use although no circuit closer will be necessary. If the crank handle is used, the lock device will still perform its func-

tion although neither clutch nor circuit closer is required. It will therefore be understood that although the machine is shown as driven by an electric motor, the construction is applicable to other types of motor 70 or means for operating the machine by hand.

The electric motor is mounted on the rear side of the machine and comprises field coils 71 surrounding an armature 72 on a shaft supporting a worm 73. This worm meshes 75 with a large gear 74 which carries a hollow cylindrical part 75 forming one of the elements of the clutch. The other clutch element comprises the plate 76 rigidly mounted on the sleeve 77 surrounding the bar 78 and 80 said element is rigidly connected to a bevel gear 79 meshed with a second bevel gear 80 mounted on the main operating shaft 81 of the machine. As shown, the bevel gear 80 is twice the size of the gear 79 so that two 35 rotations of the gear 79 and therefore of the clutch, are required to give the requisite one rotation of the operating shaft 81. The shaft 43 of Fig. 1 which is rotated when the key 52 is depressed also carries a crank arm 90 81^a, the bifurcated ends of which surround an anti-friction roller 82 on a lock lever 83. This lock lever is mounted to rotate about a pin 84 and is provided with an extended arm 85 adapted to engage a projection movable 95 with the part 76 of the clutch and thereby serves to prevent the operation of the machine. It will be seen from Fig. 3 that when the shaft 43 is rotated, the lever 83 will rock upwardly and it will thereby release 100 the operating mechanism of the machine.

In cases where the crank handle was used such handle would be connected in place of the clutch part 76 so that the movement of 105 the lock lever 83 would withdraw the lock and therefore allow a simple operation of the handle. The clutch is used to prevent an undue strain on the mechanism at the close of the operation. It is necessary in 110 machines of this type that the machine should be brought completely home at the end of each operation but if it is desired to accomplish this end with a motor machine the throwing of a positive lock into the path 115 of some moving part will cause a great strain on the parts when the locking takes place, due to the inertia of the rapidly moving parts. If, however, the motor is connected through a clutch, the mechanism 120 may be brought completely up to its home position and the motor allowed to run on as long as its momentum will carry it without any resulting damage to the mechanism.

The connection between the cylindrical 125 part 75 and the cutaway plate 76 of the clutch is accomplished by rollers 87 moving in the cutaway parts of said plate. This type of clutch is now generally well known. The movement of the cylinder 75 tends to 130

carry the rollers 87 to the narrower parts of the slots in which they are placed thereby rigidly binding together the two parts of the clutch. These rollers 87 are mounted on pins 88 carried by a nearly circular plate 89 mounted loosely on sleeve 77 and capable of a slight movement relative to the plate 76.

Plungers 89^a shown in dotted lines are spring pressed to normally move the rollers 87 toward the narrower parts of the containing slots. The mechanism in Fig. 3 is shown in normal position and it will be clear that when the machine is released in the manner before described, the arm 83 will be rocked around its pivot pin 84 and the locking end thereof carried away from the clutch. As one of the projections of the locking lever 83 is in the path of the plate 89, the withdrawal of the lever will release the springs of the plungers 89^a and will force the anti-friction rollers to the narrower parts of their containing slots. If the machine was driven for example by a belt, such belt might be passed around the cylindrical part 75 of the clutch and in such case the described release of the mechanism would immediately lock the clutch parts together and cause a complete operation of the machine. As the end of the operation is reached, the lock arm 83 is positively moved back to lock position of the fingers and the projection of plate 89 will finally contact the end 85 of said lever 83 thereby stopping the plate 89. The clutch parts would, however, move slightly forward but inasmuch as this forward movement would press the springs of the plungers 89^a and move the rollers to the wide parts of their containing slots, the clutch would then be disconnected and the machine stopped although the cylindrical part 75 of the clutch may remain in motion.

The lock relation of the arm 83 with the plate 89 might be depended upon to completely arrest the mechanism but another disk 92 is provided besides said plate 89 and which is movable with the clutch part 76. A projection on this second disk is adapted to be engaged by a projection 93 of the lock arm 83. When an electric motor is used to drive the machine it is of course necessary to close the motor circuit and to accomplish this function, an additional disk 95 is mounted loosely on the sleeve 77 and is connected to the plate 92 by a spring 96. This spring passes around the pin 97 on the plate 92 and the pin 98 on plate 95. As shown, the plate 95 has a cutaway portion 99 in which is normally placed an anti-friction roller 100 on the bell crank lever 101 journaled on the pin 102. The plate 95 has fastened thereto a lug 103 one end of which engages in a normal position of the parts with a third projection 104 of the lock lever 83 thereby retaining the spring 96 under

tension. When the machine is released, lever 83 moves from in front of the lug 103 and the spring 98 will then throw the plate 95 rapidly around until the pin 97 is reached by the other end of the slot 105 in plate 95 in which said pin moves. Clearly this movement of plate 95 will carry the cutaway portion thereof away from the roller on lever 101 and thereby rapidly rotate said lever around its pivot pin. The arm 102^a of said lever is adapted to engage the anti-friction roller 103^a on the circuit closing arm 104^a which is pivoted at 105^a and carries an insulating strip 106 directly over a spring contact strip 107. When plate 95 is rotated the lever 101 rocks and spring contact 107 is quickly depressed until it engages the stationary contacts 108 thereby closing the motor circuit.

Near the end of the operation lock lever 83 moves downwardly again bringing its projection 104 into the path of the lug 103 thereby stopping disk 95. The cutaway portion 99 of this plate is then opposite the roller 100 but the rocking of the lever 101 is still prevented by lock plate 92 and the circuit is thereby retained closed until the depressed portion of said plate 92 reaches roller 100 whereupon the spring contact 107 rises breaking its circuit and moving the lever 101 so that the roller 100 is again in the cutaway portion of both plates 92 and 95.

It will be clear from the preceding description that in the normal position of the parts both plates 92 and 95 have a cutaway portion opposite the rollers 100 of lever 101 but that when the plate 95 is released by a movement of lock lever 83 the cutaway portion of said plate is thereby carried away from the roller and the circular portion of the plate moves opposite said roller. Even after the clutch has made one complete rotation, the circuit controlling lever 101 is still held in closing position inasmuch as the cutaway portions of plates 92 and 95 are on different radial lines. At the end of the second rotation of the clutch, however, lock lever 83 is again moved to lock position and the plate 95 held stationary while plate 92 moves up until the original relative position of the two plates is restored and it is only when both depressed portions of the plates 92 and 95 are on the same radial lines that the spring contact 107 may break the circuit. As the mechanism is shown, two rotations of the clutch are necessary at each operation but clearly as many rotations as desired could be had inasmuch as it is the movement of lock lever 83 to lock position that really controls the breaking of the circuit and not the mere return of plate 95 to its original position.

In order to accomplish the return of the locking device to normal locking position the main operating shaft 81 is provided with

a cam 116 shown in Fig. 1 adapted to engage an anti-friction roller 117 on the toggle arm 34 near the end of the rotation of said shaft. When cam 116 engages the roller 117 the locking mechanism will be positively restored to normal position, the toggle arms being moved to depress the center pivot below the line joining the pivots 35 and 36. The return of the locking device moves the crank arm 50 withdrawing the projection 51 from in front of the detent pin 56, whereupon the key spring together with the detent pin immediately return the detent plate and the depressed keys to their normal position.

It was stated that the mechanism described compelled a proper sequence of operation of the transaction lever and bank of keys. It is possible to depress one of the keys 52 but there is nothing to hold the key detent in adjusted position so that the key spring would cause immediate return of the key to normal position. It would, however, be possible to retain the key depressed and the pin 56 on the segmental detent 55 thereby moved from over the projection 51 of lever 50 and if this was done the pinching of lever 16 would release the mechanism. The same effect would be produced if a key was held in depressed position at the end of an operation of the machine and the lever 16 again pinched. To prevent such manipulation of the mechanism the crank arm 50 is provided with a pawl 201 as shown on Fig. 2. This pawl is pivoted to the arm 50 at 202 and provided with a spring 203 connecting the pawl and the crank arm and tending to force the pawl into the position of the figure in which the pin 204 on the pawl engages one side of the crank arm 50. The upper end of pawl 201 is provided with a notch 205. The base of the notch 205 is slightly more distant from the center shaft 14 than is the upper end of the projection 51. If a key 52 is depressed, the detent pin 56 will be raised from over the projection 51 but will then be over the upper end of pawl 201 so that even if the lever is pinched the pawl will prevent a releasing movement of the mechanism. If the lever is pinched first and the key then operated the movement of the toggle past the center due to the arm 31 will permit a rocking of crank arm 50 until the projection 51 engages the detent pin 56. This movement of the crank arm 50 will move the pawl 201 so that its notch 205 is slightly above the base of pin 56. The movement of pin 56 will therefore engage and rock the pawl 201 so that when pin 56 passes above the projection 51 a complete releasing movement may then be obtained. At the end of the operation if the key 52 is held depressed the cam 116, when it restores the toggle, will rock the crank arm 50 carrying the pawl 201 so that its notch is below the

pin 56. If attempt is then made to pinch the lever without releasing the key, the pawl will rise slightly until it engages under the pin 56 producing precisely the position of the parts previously described, and the release mechanism will still be inoperative. The space between the projection 51 and the pawl 201 is narrower than the pin 56 so that it would be impossible to depress key 52 and then operate the lever and partly release the key with the anticipation that pin 56 would ride from over the notch 205 on pawl 201 before it obstructs the movement of pawl 51. The pin 56 will, on the contrary, move over the projection 51 before it releases pawl 201 and when a sufficient downward movement is given the pin 56, to completely remove it from the path of pawl 201, the projection 51 will then be under pin 56 and a slight rotation permitted crank arm 50 due to the fact that pawl 205 is at a slightly greater elevation than the projection 51 will permit spring 41 to rock the crank arm 50 until projection 51 engages and is stopped by pin 56. It will be seen that this safety pawl 201 effectively prevents an operation of the mechanism except in the desired sequence.

As the mechanism has been described the circuit for the motor is broken at the end of each operation, although there is no positive stop for the motor. It would therefore follow that the motor would continue to run after the clutch parts have been separated until its momentum was exhausted. Under some conditions especially with alternating current motors it may be advisable to continue the motor moving between operations. If the motor stops it requires some time to bring it up to speed and as at this time the whole load of the register is on the motor its acceleration is relatively slow which of course lowers the average speed of operation of the machine. If the motor may run constantly at or near its full speed it will pick up the machine much more rapidly and thereby render possible much faster operation of the machine.

To provide means whereby the motor may run constantly yet without the use of much current the construction shown in the diagram, Fig. 7 may be employed. It will be understood that the motor will not need much current to maintain it at full speed when there is no load thereon. There is provided a shunted resistance around the circuit closer for the motor, this resistance being preferably inductive in the case of alternating current machines. When the machine is to be operated the circuit closer short circuits the inductive resistance, thereby permitting the full current to pass through the motor and as the motor is already up to speed a very quick operation of the machine will result. At the end of the operation the circuit closing contacts will

part, thereby throwing all the line current through the inductive resistance. This will decrease materially the strength of current, but enough will be left to maintain the motor at speed as there is then no load thereon.

The motor circuits are shown in Fig. 7. The power is derived from a battery or other generator 250 from which extend line wires 251 and 252. These may in practice be 10 incandescent light wires or any other convenient power circuit. Connecting with wire 252 is a lead wire 253 running to a switch 254 of any desired form, though preferably this switch is of some well known 15 snap variety. From the switch a wire passes through a fuse block 255 and a wire 256 to a machine terminal 257. From the other line wire 251 a wire 258 leads to a second machine terminal 259. From terminal 257 20 a wire 260 leads to the field coils 71 and the armature 72 of the motor which is herein shown as of a series type but may equally well be a shunt or compound wound machine. From terminal 259 two wires lead, 25 one numbered 263 passing to a condenser 264 from the other side of which a wire 265 leads to the contact terminal 108. A second wire 266 from terminal 259 leads to a wire 267 running to contact strip 107^a. From the 30 field coil 71 a wire 261 leads through a rheostat 262 and a wire 263 to the other contact terminal 107. Across the two terminals is a shunt comprising wires 268 and 270 with a resistance 269 which for alternating current machines may preferably be of an inductive type as shown in the drawing. During the preceding description of the machine the contact terminal was stated to be single but in reality it comprises two strips 35 107 and 107^a as shown on this figure, the purpose of this double contact being to prevent sparking when the circuit is broken. Assuming the snap switch 254 to be closed as would normally be the case in practice, 40 it will be seen that the motor circuit is complete. This circuit includes the generator 250, wire 252, wire 253, switch 254, fuse block 255, wire 256, terminal 257, wire 260, field coils 71, armature 72, wire 261 rheostat 262, wire 45 263, wire 270, resistance 269, wire 268, wire 266, terminal 259, wire 258, and wire 251 back to the generator. The current passing will be proportionate to the resistance in the circuit and will be largely determined by 50 the resistance 269. Enough current will pass to maintain the motor at speed as there is no load thereon. When the machine is operated and the circuit closing lever 101 rotated around its pivot 102 the contact terminals 107 and 107^a are brought into contact with the plate 108. It is intended that 55 terminal 107 shall engage plate 108 slightly before the contact of terminal 107^a. Without tracing the circuits in detail it will be seen

that when contact 107 engages the plate 108 65 a circuit is made including the condenser 264 but not including the inductive shunts 269. When, an instant later the terminal 107^a also contacts plate 108 the condenser is short circuited and the necessary amount 70 of current will then pass through the motor. At the end of the operation the contact terminals 107 and 107^a are permitted to break circuit, 107^a moving from contact before 107 and the condenser is then thrown into 75 circuit for an instant followed by the shunting of all the current through the resistance 269.

It follows from the construction described that the condenser 264 is only in the main 80 circuit for the instant when the spark would occur inasmuch as the contact of terminal 107^a with plate 108 almost immediately follows the contact by terminal 107. The use of the shunt resistance 269 is of particular 85 value in connection with alternating current machines. With the shunt resistance for direct current machines and especially for alternating current commutating machines the amount of current passing between operations will be merely enough to keep the speed of the motor up so that it will quickly start the machine when the clutch parts are connected and at the same time the resistance 269 is short circuited by the contact 90 terminals so that the full current passes through the motor causing a quick operation of the machine.

The rheostat 262 is of value in cases where it is desired to use an alternating current 100 motor on a direct current circuit. As the motor is shown it may be used with alternating currents, it being a commutating type motor. Assuming for example that the motor was intended to be used on a 110 105 volt alternating circuit, if it was desired to use it on a direct current circuit of 110 volts the resistance of the machine would not be sufficient to keep down the current due to the fact that there would be no inductance caused by the direct current. In this case the rheostat 262 may be employed, thereby cutting down the current enough to run the motor satisfactorily.

While the form of mechanism herein 115 shown and described is admirably adapted to fulfil the objects primarily stated, it is to be understood that it is not intended to confine the invention to the one form of embodiment herein disclosed, for it is susceptible 120 of embodiment in various forms all coming within the scope of the claims which follow.

What is claimed is as follows:

1. In a registering mechanism, the combination with a lock for the mechanism, of a spring for moving said lock, a toggle connected to said lock and preventing said

- spring from operation, and a manipulative device for breaking said toggle and permitting said spring to move said locking device. 65
2. In a registering mechanism, the combination with a main operating mechanism, of a locking device therefor, a toggle connected to said locking device and normally holding the same in locking position, manipulative means having connections to break said toggle, and a spring connected to said locking device and constructed to move it to unlocking position when said toggle is broken. 70
3. In a registering mechanism, the combination with a locking device for said mechanism, a toggle device normally preventing releasing movement of said locking device, means for breaking said toggle device and means made effective by breaking said toggle device for moving said locking device to 75 releasing position. 80
4. In a registering mechanism, the combination with a driving mechanism, of means for locking same, a toggle connected to said locking means and preventing movement of same to releasing position, means for breaking said toggle, and a spring for moving said locking means after said toggle has been broken. 85
5. In a registering mechanism, the combination with a driving mechanism, of means for locking same, a spring for moving said locking means to releasing position, a toggle holding said locking means, and a manipulative device for breaking said toggle to permit said spring to operate. 90
6. In a registering mechanism, the combination with a driving mechanism, of means normally locking same, a toggle connected to hold said locking means in locking position, means for breaking said toggle to permit the operation of said locking means, means for moving said locking means after said toggle is broken, and devices operated by said driving mechanism for straightening said toggle and thereby restoring said locking means to locking position. 95
7. In a registering mechanism, the combination with a driving mechanism, of means normally locking same, a spring for moving said locking means to releasing position, devices for holding said locking means against movement, a lever having a plurality of positions and connections whereby any movement of said lever operates said holding devices. 100
8. In a registering mechanism, the combination with a main driving mechanism, and means normally locking the same, of a hand operated lever and a bank of keys, connections from said lever for moving said locking device toward unlocking position, and obstructing devices for said locking means constructed to be withdrawn by any key of said bank. 105
9. In a registering mechanism, the combination with a main driving mechanism, of means normally locking the same, a hand lever and a bank of keys, a spring connected to said locking means and normally tending to move the same to unlocking position, connections from said hand lever for moving said locking means toward unlocking position, and obstructing devices preventing complete release of said locking means and constructed to be withdrawn by any key of said bank. 110
10. In a machine of the class described, the combination with a driving mechanism including a rotary shaft, of means normally locking said shaft a spring for releasing said locking means, mechanism normally preventing said spring from operating, manipulative means, an adjustable manipulative device, and connections requiring the operation of the manipulative means and the adjustable manipulative device to withdraw said preventing mechanism and permit said spring to operate. 115
11. In a registering mechanism, the combination with a driving mechanism, of a locking means therefor, a plurality of manipulative devices all normally operative, means operated by one of said devices for partially operating said locking means, and devices operated by another of said manipulative devices permitting said locking means to move to completely releasing position. 120
12. In a registering mechanism, the combination with a main driving mechanism, and means normally locking the same, of a device normally holding said locking means against releasing movement, a hand lever having connections to disable said holding device, a bank of keys, and a device normally obstructing releasing movement of said locking means, constructed to be withdrawn by any key of said bank. 125
13. In a registering mechanism, the combination with a driving mechanism and a locking means therefor, connections from said locking means preventing movement thereof, a hand lever, devices moved from said lever for disabling said connections, a key, and means moved thereby and normally preventing movement of said connections but movable out of the path of said connections by said key. 130
14. In a registering mechanism, the combination with a driving mechanism, and locking means therefor, a toggle connected to said locking means and normally straightened to prevent movement of said means, a hand lever and connections for breaking said toggle, a series of keys, a detent plate moved by said keys and a pin on said plate in position to prevent complete movement of said locking means after said toggle has been broken, but which permits releasing

movement of said locking means after adjustment of said key.

15. In a registering mechanism, the combination with a driving mechanism, and a locking means therefor, of connections including a normally straightened toggle for preventing movement of said means, a manipulative device and connections for breaking said toggle, and means preventing release of said locking means after said toggle is broken until said manipulative device and connections are restored to normal position.

16. In a registering mechanism, the combination with a driving means, of a mechanism driven thereby, means for locking said driven mechanism, a clutch for controlling said driven mechanism retained in unclutching relation by said locking means, manipulative devices for releasing said locking means and thereby permitting said clutch to act, and connections from said driven mechanism for positively restoring said locking means to locking position.

17. In a registering mechanism, the combination with a driving means, of a mechanism driven thereby, a friction clutch for connecting said driving means and driven mechanism, an arm constructed to lock said driven mechanism against operation and to retain the clutch parts in unclutching relation, keys controlling the movement of said arm, and means operated by said driven mechanism for restoring said arm to a position to lock said driven mechanism and uncouple said clutch parts.

18. In a registering mechanism, the combination with a driving means, of a registering mechanism driven thereby, a clutch including clutching rolls for connecting said driving means and registering mechanism, a spring for moving said rolls to clutching position, an arm for locking said mechanism and holding said rolls in unclutching position, keys for moving said arm, and connections from said driven mechanism for restoring said arm to locking position.

19. In a machine of the class described, the combination with a main driving mechanism, of a toggle-joint having connections preventing operation of said driving mechanism while said toggle is straightened, and means for breaking said toggle-joint and thereby disabling said connections.

20. In a registering mechanism, the combination with a driving mechanism, of means for locking same, a toggle-joint connected to control said locking means, a spring mounted to force the toggle-joint to either side of a center line passing through its pivots, a manipulative device for breaking the toggle-joint, and means operated by the driving mechanism for restoring the toggle-joint to original condition.

21. In a registering mechanism, the combination with a driving mechanism, of

means for locking same, a toggle-joint connected to control said locking means, a spring mounted to force the toggle-joint to either side of a center line passing through its pivots, and a manipulative device for 70 breaking the toggle-joint.

22. In a registering mechanism, the combination with a driving mechanism, of a motor for operating the same, a motor switch having spring means to open the 75 switch, a pivoted lever for controlling said spring means, a pair of relatively movable notched disks controlling said lever, the notches normally permitting the switch to remain in open position, a spring for moving 80 said disks relatively and thereby through the lever closing the switch, and means operated by the driving mechanism for restoring the relative relation of said disks and thus permitting the switch to open.

23. In a registering mechanism, the combination with a driving means, and a mechanism driven thereby, of a clutch for connecting said driving means to said driven mechanism, a pivoted arm normally retaining the parts of said clutch in unclutching relation, and also locking said driven mechanism against operation, keys having connections for controlling the movement of said pivoted arm, and a cam, actuated by 90 said driven mechanism and positioned to control restoration of said pivoted arm to normal position.

24. In a machine of the class described, the combination with a series of depressible 100 but normally unarrestable keys, of means, normally inoperative, for arresting said keys when depressed, and adjustable manipulative means for rendering said arresting means operative.

25. In a machine of the class described, the combination with an operable but normally unarrestable key, of means, normally inoperative, for arresting said key when operated, and an adjustable manipulative 110 device for rendering said arresting means operative.

26. In a machine of the class described, the combination with an operable but normally unarrestable key, of means, normally inoperative, for arresting said key when operated, and a differentially adjustable manipulative device for rendering said means operative.

27. In a machine of the class described, the combination with an operable but normally unarrestable key, of a plate actuated by said key, a normally inoperative latching device for said plate, and adjustable manipulative means for rendering said latching device operative whereby the key when operated will be arrested by the plate.

28. In a machine of the class described, the combination with an operable but normally unarrestable key, of a plate actuated 130

by said key, a normally inoperative latching device for said plate, and a differentially adjustable manipulative device for rendering said latching device operative whereby 5 the key when operated will be arrested by the plate.

29. In a machine of the class described, the combination with a series of operable but normally unarrestable keys, of a differentially adjustable manipulative device, and means under the control thereof for arresting any key of the series when operated. 10

30. In a machine of the class described, the combination with a series of operable but normally unarrestable keys, of a detent plate common to said keys, a normally inoperative spring actuated latching device for said detent plate, and a differentially adjustable manipulative device for rendering 15 said latching device operative whereby any of the keys when operated will be arrested by the detent plate. 20

31. In a machine of the class described, the combination with an operating mechanism, of means preventing the actuation 25

thereof, an operable but normally unarrestable key, means, normally inoperative, for arresting the key when operated and for controlling the actuation of the preventing means for the operating mechanism, and an 30 adjustable manipulative device controlling said arresting means.

32. In a machine of the class described, the combination with an operating mechanism, of means preventing the actuation 35 thereof, an operable but normally unarrestable key, means, normally inoperative, for arresting the key when operated and for controlling the actuation of the aforesaid preventing means, and a differentially adjustable manipulative device for controlling 40 said arresting means.

In testimony whereof we affix our signatures in the presence of two witnesses.

CHARLES F. KETTERING.
WILLIAM A. CHRYST.
